DESIGN FOR A ROULETTE BOARD

Charles A. Anderson, New Rochelle, N. Y., assignor to Gotham Pressed Steel Corporation, New York, N. Y., a corporation of New York

Application August 7, 1933, Serial No. 48,955

Term of patent 3½ years

To all whom it may concern:

Be it known that I, CHARLES A. ANDERSON, a citizen of the United States, and resident of New Rochelle, in the county of Westchester and State of New York, have invented a new, original, and ornamental Design for a Roulette Board, of which the following is a specification, reference being had to the accompanying drawing, forming a part thereof.

Fig. 1 is a plan view of my roulette board, and Fig. 2 is a side view of same.

I claim:

The ornamental design for a roulette board as shown.

CHARLES A. ANDERSON.
